UNITED STATES PATENT OFFICE.

SIMEON S. JACKSON, OF BOSTON, MASSACHUSETTS, ASSIGNOR TO THE STAFFORD COMPANY, OF READVILLE, BOSTON, MASSACHUSETTS, A CORPORATION OF NEW JERSEY.

WEFT-PARTER DEVICE FOR LOOMS.

1,023,108.

Specification of Letters Patent.

Patented Apr. 9, 1912.

Application filed January 17, 1912. Serial No. 671,585.

To all whom it may concern:

Be it known that I, SIMEON S. JACKSON, a subject of Great Britain, residing at Readville, Boston, in the county of Suffolk, State 5 of Massachusetts, have invented a certain new and useful Improvement in Weft-Parting Devices for Looms, of which the following is a specification, reference being had therein to the accompanying drawings.

10 The invention is designed to be used in looms of the class operating to effect replenishment of the working weft-supply automatically by ejecting the working shuttle from the lay and placing a fresh or reserve 15 shuttle on the lay to continue the weaving. Looms of the said class are shown and described in U. S. Letters Patent No. 870,509, granted Nov. 5, 1907, and No. 945,722, granted Jan. 4, 1910. In such looms the 20 mechanism thereof effects the ejection of the working shuttle by first raising the front-plate of the shuttle-box which is occupied by the said shuttle, and then pushing the shuttle forward on the lay-beam past the 25 uplifted front-plate and from the lay-beam so that it drops down in advance of the lay into a stationary catcher-box located at the front of the loom. Patent No. 870,509 aforementioned also shows and describes the employment 30 of feeler-mechanism operating to bring about the ejection of the working shuttle and the introduction of a fresh or reserve shuttle shortly before the supply of weft or filling contained in the working shuttle has 35 become completely exhausted. When the working shuttle of a loom is expelled prior to complete exhaustion of its supply of weft or filling, the portion of yarn that extends from the selvage of the cloth to the said 40 shuttle, forming a continuation of the last pick of weft or filling laid among the warp-threads, hangs down between the lay and breast-beam to the said shuttle in the catcher-box.

45 The invention consists in novel means of supporting the said portion of yarn, and presenting it to the action of a weft-parting device located adjacent the selvage of the cloth, so as to insure that it shall be parted or severed 50 by the action of such device.

In the drawings,—Figure 1 shows in side elevation certain portions of a shuttle-changing weft-replenishing loom having an embodiment of the invention applied thereto. Fig. 2 shows in plan the parts that are

represented in Fig. 1. Fig. 3 is a sectional view showing a modification. Fig. 4 is a plan view showing the said modification.

Having reference to the drawings, and first to Figs. 1 and 2,—the loom-frame is 60 marked 1, the breast-beam 2, the lay 3, and the lay-beam 3^a. The drawings show certain features of replenishing mechanism on the order of what is presented in the patents aforesaid, as follows: The vertically-mov- 65 able front-plate of the shuttle-box at the magazine-side of the loom is shown at 4, 5 being its carrying or supporting rocker, hung upon the lay, and 6 a rod connecting the said rocker with a lever 7, which last 70 is actuated in one direction by a cam 8 on the change-shaft 9 to swing the rocker to raise the said front-plate. At 10 is an ejector which is actuated by the rocker as the front-plate is raised, and when thus op- 75 erated pushes the working shuttle forward across the top-surface of the lay-beam and off from the latter.

10^a is a flexible apron, connected at its upper end to the lay-beam, and down which 80 the ejected shuttle slides into the catcher-box 10^b which is mounted upon the loom-frame in advance of the lay and below the magazine.

11 is a spring which retracts the ejector as 85 the front-plate closes down into working position under the action of a spring 12 en- gaging with the rocker. By means of the spring 12 the front-plate is swung down into 90 normal position in front of the fresh shuttle after the latter has been placed upon the lay, so as to inclose such shuttle within the shuttle-box in condition for continuation of the weaving process. At 13 is a magazine 95 for reserve shuttles, and 14 is a transfeerer by which a reserve shuttle is transferred from the mouth of the magazine to the lay. The said transfeerer being pivoted at 15, and being operated by means of a cam 16 on the change-shaft, and a spring 17, the said cam 100 serving to move the transfeerer forward to its normal retracted position shown in Fig. 1 of the drawings, and the said spring serv- 105 ing to move the transfeerer rearward, under the control of the said cam, to effect the transfer of a reserve shuttle from the maga- zine to the lay. At 18 is a peg or pin sup- 110 ported by the magazine and to which are attached the starting-ends of the loads of weft or filling which are contained in the re-

serve shuttles that occupy the magazine, and 19 is a wire, attached to the magazine at the rear of the latter, and constituting a weft-end holder around the inner end of which 5 the starting-end of the weft or filling carried by the freshly transferred shuttle, and extending from the latter to the peg or pin 18, loops as the said shuttle makes its first flight from the magazine-side of the loom to 10 the other side of the latter. The starting-end *a* thus looped around the inner end of the weft-end holder 19 extends obliquely downward and rearward from the bend at the inner end of the said weft-end holder to 15 the selvage of the cloth.

At 20 is a loom-temple located at the magazine-side of the loom and equipped with a weft-parter, usually termed a temple-cutter, which may be of any approved character and construction suitable for the purpose of cutting the starting-end *a* as soon as the first pick of the fresh weft is beat up by the lay. The temple-head is shown provided with a mouth or notch 20^a into which 25 the yarn to be parted or severed finds its way, and with a pivoted blade-member 20^b that is actuated in one direction by engagement of the lay-beam with its heel 20^c as the lay beats up, and in the other by a spring 30 (not shown) as the lay recedes. The said blade-member operates in its movement to part or sever the yarn that has entered into the mouth or notch.

When the front-plate 4 is raised and the 35 shuttle is pushed forward and drops down between the front of the lay-beam and the magazine, the portion *b* of weft-thread or filling forming a continuation of the pick just laid among the warp-threads by the 40 flight of the shuttle to the magazine-side of the loom, and extending outward from the selvage at that side, will draw downward away from the temple-cutter and not be acted upon by the latter unless means is provided for preventing it from drawing out 45 of the range of action of the temple-cutter.

In accordance with my invention I provide novel means of preventing the outwardly extending portion *b* of weft or filling from sinking, adjacent the selvage, too 50 low to be acted upon by the temple-cutter or weft-parter; and also presenting the said portion to the temple-cutter or weft-parter to be cut or parted thereby. The said means 55 may be of the character and construction shown in Figs. 1 and 2, or may be of the character and construction shown in Figs. 3 and 4.

Referring first to Figs. 1 and 2, *c* represents 60 a rod or wire which is attached by one end thereof to a stand *d* that is fixed upon the breast-beam 2. Thereby the said rod or wire *c* is mounted in stationary position upon the loom-frame adjacent the selvage and the temple-cutter or weft-parter. It

extends rearward in the loom toward the lay. The attachment of the rod or wire to its supporting bracket may be effected conveniently in the manner shown, namely by inserting the forward end of the rod or wire through a hole in the said stand and securing it therein by collars *e*, *e*, fixed upon the rod or wire at front and rear of the stand and fitting against the opposite faces of the latter. The rod or wire is adjustable lengthwise in the direction from front to rear in the loom. For convenience in applying and adjusting the rod or wire, the said forward end of the rod or wire may be screw-threaded and the collars *e*, *e*, constituted by nuts, with said nuts screwed upon the rod or wire tightly against opposite sides of the stand. The rear end of the rod or wire drops slightly below the height of the upper surface of the lay-beam, and to accommodate such end a groove *f* is formed in the top of the lay-beam. As the lay swings forward the length of weft or filling lying upon the top surface of the lay-beam and extending from the selvage to the shuttle in the adjacent shuttle-box simply passes forward above the rear end of the rod or wire.

The forward portion of the rod or wire is elevated, and is so related to the opening or mouth of the temple-cutter or weft-parter that forward movement of a portion of weft or filling extending outward and over the rod or wire, and hanging down to the ejected shuttle, will carry the same into the said opening or mouth into position to be acted upon and parted or severed by the temple-cutter or weft-parter.

The rod or wire *c* does not interfere with the running weft so long as the working shuttle is regularly in action. When, however, the said shuttle is ejected or expelled by being pushed forward off the lay and drops down along the apron 10^a into the catcher-box 10^b the said rod or wire serves to support, adjacent the selvage and temple-cutter or weft-parter, the portion *b* of weft or filling extending outward from the selvage and down to the expelled shuttle in the catcher-box, and facilitates the entry of the said portion *b* into the mouth of the temple-cutter. As the shuttle falls forward from the lay-beam in being ejected, and slides forward down the flexible apron 10^a, the said portion *b* of weft or filling is thrown forward somewhat, and also is drawn forward by reason of the forward movement of the shuttle in finding its way into the catcher-box. This action may be utilized, alone, in depositing the said portion *b* of weft or filling upon the rod or wire. After the resumption of weaving, the action of the reed carried by the lay also will serve to carry the said portion of weft or filling forward as the lay beats up. The advance of the cloth as the latter is taken up also

will carry the said portion forward. One or another of these causes may be depended upon, if deemed desirable, to bring about the entrance of the portion *b* of weft or 5 filling into the range of action of the weft-parter so that it will be parted or severed by the latter. To prevent the said portion *b* of weft or filling from shifting rearward again, a notch *c'* is provided in the top side 10 of the rod or wire *c* to receive and engage the same. The said notch is located in advance of the mouth of the temple-cutter, *i. e.*, farther toward the front of the loom, so that when the yarn is in the said notch and 15 detained thereby the yarn extends at a forward inclination outward from the selvage through the notch and thereby is held in position to enter and remain within the mouth of the temple-cutter.

20 Figs. 1 and 2 show the employment of a piece *g*, fixed upon the front of the lay-beam 3^a to coöperate with the rod or wire *c*. The said piece *g* extends forward from the lay-beam alongside the rod or wire. As the 25 lay swings rearward the acting portion of the piece *g* rises with relation to the rod or wire and passes slightly above the latter as in Fig. 1. Should the working shuttle be pushed forward from the lay-beam while 30 the lay is rearward, the portion *b* of weft or filling extending from the selvage to the ejected shuttle will land upon the rod or wire *c* in advance of the acting portion of said piece *g*, or upon the piece *g*. In 35 case the said portion of weft or filling falls upon the acting portion of the piece *g*, it will follow that when the weaving mechanism is restarted on the completion of the replenishing operations the said piece *g* will 40 carry the said portion *b* forward until the downward swinging movement of the piece *g* depresses its top surface below the rod or wire *c* and deposits the said portion *b* of weft or filling upon the forward part of the 45 rod or wire. In being thus deposited the weft or filling usually will pass or be thrown so far forward that it will not be engaged by the piece *g* and carried backward in the loom by such piece as the rearward 50 stroke of the lay causes the acting portion of said piece to rise again above the rod or wire.

The forward end of the piece *g* is shaped properly to push the weft or filling *b* forward as the lay advances, when the said weft or filling rests on the rod or wire within reach of such end. When the piece *g* is employed, the rod or wire *c* need extend rearward only far enough to lap the forward or acting end of the said piece in the most rearward position of the lay.

In Figs. 3 and 4 the rod or wire, therein marked *c'*, is of sufficient length rearward of the breast-beam to enable its rear portion 65 to occupy the groove *f* in the lay-beam in

all positions of the lay, the said rear portion being depressed so as not to interfere with the shuttle in its flight. Consequently, at whatever point in its stroke the lay may come to rest when the weaving mechanism of the 70 loom is stopped for the performance of the replenishing operations, the rear portion of the rod or wire will occupy the groove in the lay-beam. The piece *g* is, or may be, omitted in case the long rod or wire *c'* is 75 employed. The rod or wire *c* or *c'* is so located below the line of the starting-end *a* of fresh weft or filling extending from the weft-end holder 19 to the selvage of the cloth that the said starting-end does not 80 come in contact with the rod or wire.

The two studs or fingers *h*, *h'*, shown mounted upon the front of the lay-beam near the inner end of the shuttle-box at the magazine-end of the loom are employed for the purpose of catching the inner end of the expelled shuttle so as to cause the said shuttle to slide down the apron 10^a with its outer end foremost. The stud or finger *h'* is a little to one side and below the stud or 90 finger *h*, in consequence of which the shuttle resting by its inner end upon the stud or finger *h* swings downward until it touches the stud or finger *h'*, assuming thereby the desired inclination, and then slides from the 95 said studs or fingers down the apron 10^a , outer end foremost, as just mentioned. The stud or finger *h*, in addition, constitutes a supplemental support, carried by the lay, for the portion *b* of weft or filling extending from the selvage to the expelled shuttle.

What is claimed is:

1. In a weft-replenishing loom in which the working shuttle is expelled forwardly from a shuttle-box on the lay, the combination with a weft-parter adjacent the selvage of the cloth, of a stationary weft or filling-support mounted adjacent the weft-parter and over which the portion of weft or filling extending from the selvage to the expelled shuttle is laid by the said shuttle as the latter falls in front of the lay, the said stationary support supporting said portion of weft or filling in position to be acted upon by the weft-parter. 105

2. In a weft-replenishing loom in which the working shuttle is expelled forwardly from a shuttle-box on the lay, the combination with a weft-parter adjacent the selvage of the cloth, of a weft or filling support 110 mounted independently of the lay adjacent the weft-parter and over which the portion of weft or filling extending from the selvage to the expelled shuttle is laid by the said shuttle as the latter falls in front of the lay, the said support supporting the said weft or filling in position to be acted upon by the weft-parter. 120

3. In a weft-replenishing loom in which the working shuttle is expelled forwardly 125

- from a shuttle-box on the lay, the combination with a weft-parter located adjacent the selvage of the cloth, of a weft-support mounted independently of the lay, and a co-operating piece, as *g*, mounted upon the lay and projecting alongside the said weft-support, over both of which the portion of weft or filling extending from the selvage to the expelled shuttle is carried by the latter as it is expelled and falls in front of the lay, said weft-support adapted to sustain said portion of the weft or filling in position to be acted upon by the weft-parter, and the said piece being adapted to place the weft or filling forward upon the weft-support.
4. In a weft-replenishing loom in which the working shuttle is expelled forwardly from a shuttle-box on the lay, the combination with a weft-parter located adjacent the selvage of the cloth, of a stationary weft-support mounted independently of the lay, and a co-operating piece, as *g*, mounted upon the lay and projecting alongside the said weft-support, over both of which the portion of weft or filling extending from the selvage to the expelled shuttle is carried by the latter as it is expelled and falls in front of the lay, said weft-support adapted to sustain said portion of the weft or filling in position to be acted upon by the weft-parter, the said piece being adapted to place the weft or filling forward upon the weft-support.
5. In a weft-replenishing loom in which the working shuttle is expelled forwardly from a shuttle-box on the lay, the combina-

tion with a weft-parter adjacent the selvage of the cloth, of a stationary weft or filling-support mounted adjacent the weft-parter and over which the portion of weft or filling extending from the selvage to the expelled shuttle is laid by the said shuttle as the latter falls in front of the lay, the said stationary support supporting said portion of weft or filling and constructed to hold it forward in position to be acted upon by the weft-parter.

6. In a weft-replenishing loom in which the working shuttle is expelled forwardly from a shuttle-box on the lay, the combination with a weft-parter located adjacent the selvage of the cloth, of a weft-support mounted independently of the lay, and a co-operating piece, as *g*, mounted upon the lay and projecting alongside the said weft-support, over both of which the portion of weft or filling extending from the selvage to the expelled shuttle is carried by the latter as it is expelled and falls in front of the lay, said weft-support adapted to sustain said portion of the weft or filling and constructed to hold it forward in position to be acted upon by the weft-parter, the said piece being adapted to place the weft or filling forward upon the weft-support.

In testimony whereof I affix my signature in presence of two witnesses.

SIMEON S. JACKSON.
